Patented Oct. 25, 1927.

UNITED STATES PATENT OFFICE.

FLOYD K. EASTMAN, OF KOKOMO, INDIANA, ASSIGNOR TO CONCEALED DOOR CHECK COMPANY, OF KOKOMO, INDIANA, A CORPORATION.

DOORCHECK.

Application filed April 23, 1926. Serial No. 104,081.

This invention pertains to a door check particularly adapted for use in connection with automobile bodies or similar vehicles.

Heretofore varying types of checks have been used originating with the ordinary exposed loop strap which would loop outwardly from the door when in closed position and be secured at both ends to the surface of the door and body. Concealed checks have been employed wherein a cable or metallic member has been slidably secured within the frame work of the body and door so as to be entirely concealed when in closed position, as well as groove and slot checks mounted on the top of the door, such types requiring shock absorbing members and being relatively expensive of manufacture and installation.

The principal object of this invention is to provide a concealed check which will be little, if any more expensive than the ordinary strap; which will have sufficient resiliency and give to absorb the shock without provision of an additional shock absorbing member, and which will assume its proper position in the frame work of the door or body so as to avoid interference with the window actuating mechanism and take up a minimum of space.

The particular features of the invention will be hereinafter fully described and set forth in the accompanying specifications and claims.

Fig. 1 is a section taken through a portion of a vehicle door and the adjacent body frame. Fig. 2 is a plan view of the check strap. Fig. 3 is a section taken on a line 3-3 of Fig. 2. Fig. 4 is a modified form of strap. Fig. 5 is a section taken on the line 5-5 of Fig. 4. Fig. 6 is the same as Fig. 1 showing the position of the strap when the door is in open position. Fig. 7 is an end elevation showing a modified form of an enlarged head. Fig. 8 is a plan view as shown in Fig. 7.

In the drawings there is illustrated a portion of a vehicle body 10 having an inner wall or covering 11 supported on the angle iron post 12. Hingedly mounted thereon in the usual manner through the medium of the hinge 13 there is a door 14 having an inner wall or covering 15 and the angle iron frame 16. As herein shown the check strap is applied to the new type of metal body construction, but is equally adapted to

use in a similar manner with respect to the wooden type of body construction. The face of the angle iron post 12 which lies adjacent the door is provided with a slot or opening 17 formed therein which abuts, when the door is in closed position, a similar slot 18 formed in the angle iron post 16.

The openings 17 and 18 are of such size and shape as to freely accommodate the check strap. It will be noted that the opening 18 is formed by stamping out a tongue in the metal post 16 and bending it back on itself to form a rounded edge 19.

The strap is formed of a double layer of fabric 20 and 21 by folding it at one end 22 and then folding the folded end over on itself to form an enlarged end member 23. The folds are secured rigidly at both ends by the rivets 24. Intermediate the layers 20 and 21 there is mounted a floating metallic strip 25 which is loosely positioned therein and spaced from the ends and sides as illustrated. Adjacent the metal strip 25 and positioned on each side thereof there are vulcanizing rubber strips 26 of substantially the same thickness as the metal strip 25. After the strap has been thus formed it is coated entirely about its surface with vulcanizing rubber 27 and vulcanized so as to give a smooth and finished appearance.

In installing the strap it is inserted through the openings 17 and 18, the thinner end thereof being bolted to the frame 12 by the bolt 28 while the remainder of the strap is adapted to slide through the opening 18 until the rounded and reinforced portion of the frame 16 engages and is stopped in its sliding movement by the enlarged end 23.

The opening movement of the door is thus limited by the enlarged head 23 of the strap, the nature thereof being such as to provide a relatively soft cushioning effect while the shock is absorbed throughout the entire length of the strap as well as the head by reason of the yielding nature of the material from which it is formed. It will be noted that the metal strip 25 floats freely within the layers of the strap and is not rigidly secured thereto. Therefore it will in no way affect the resiliency thereof. The function of the metal strip 25 is to prevent any buckling of the strap, as well as retain it in proper position adjacent the wall or covering 15 of the door and out of the way of any mech-

anism contained therein. This gives the strap an added rigidity so as to retain its proper form and position, while at the same time in no way affecting its resiliency.

- 5 In the modified form shown in Figs. 4 and 5 there is provided a single layer of fabric 121 on one surface of which the metal strip 125 is mounted, said strip being anchored thereto by the rivet 126 at one end 10 and extending into a U-shaped metallic head or enlarged member 123 secured to the other end of the strap. This construction is illustrated as being applicable to cheaper and lighter types of bodies.
- 15 Whereas the check herein illustrated and described has been shown as applied to a metal body structure, it is equally applicable to use in connection with a wooden structure.
- 20 In a modified form shown in Figs. 7 and 8, the enlarged head is secured by inserting a pin 224 in the folded end of the strap so as to extend between the layers 220 and 221. The pin will expand the layer so as to increase the thickness of the strap at the end 25 and thereby secure the enlarged head 223. The entire surface of the strap and enlarged head may then be vulcanized so as to have a rubber covering 227.
- 30 The invention claimed is:
1. A check for limiting the opening movement of a door comprising a fabric strap, an enlarged head on one end thereof, and a metal strip mounted intermediate the ends thereof so mounted thereon as to maintain said strap normally in a straight line and prevent buckling thereof while freely permitting longitudinal resiliency.
  2. A check for limiting the opening movement of a door comprising a strap, an en-

larged head secured to one end thereof, and means associated with said strap for normally maintaining it in a substantially straight line while freely permitting longitudinal resiliency thereof.

3. A check for limiting the opening movement of doors comprising a fabric strap formed with a plurality of layers, one end thereof being folded over on itself to secure an enlarged head, and a metallic strip positioned intermediate said layers for normally maintaining said strap in a straight line and preventing buckling thereof, while permitting longitudinal resiliency.

4. A check for limiting the opening movement of doors comprising a fabric strap formed with a plurality of layers, one end thereof being folded over on itself to secure an enlarged head, a member positioned in said folded end, a metallic strip positioned intermediate said layers for normally maintaining said strap in a straight line and preventing buckling thereof, while permitting longitudinal resiliency, and a vulcanized coating of rubber surrounding said strap and strip for enclosing the same.

5. A check for limiting the opening movement of doors comprising a fabric strap formed with a plurality of layers, one end thereof being folded over on itself to secure an enlarged head, and a flexible metallic strip positioned intermediate said layers and extending substantially from one end of said strap to the other for normally maintaining said strap in a straight line and preventing buckling thereof, while permitting longitudinal resiliency.

In witness whereof, I have hereunto affixed my signature.

FLOYD K. EASTMAN.
